UNITED STATES PATENT OFFICE.

PHILLIP HIEN, OF CHICAGO, ILLINOIS, ASSIGNOR TO DAVID S. WEGG, OF SAME PLACE.

DESIGN FOR A LIFTING-PIN FOR CAR-COUPINGS.

SPECIFICATION forming part of Design No. 33,755, dated December 18, 1900.

Application filed November 24, 1900. Serial No. 37,685. Term of patent 14 years.

To all whom it may concern:

Be it known that I, PHILLIP HIEN, a citizen of the United States, and a resident of Chicago, in the county of Cook and State of Illinois, have invented and produced a new and original Design for a Lifting-Pin for Car-Couplers, of which the following is a specification, reference being had to the accompanying drawings, and to the letters of reference marked thereon, which form a part thereof.

In said drawings, Figure 1 is a side elevation of said lifting-pin embodying my design. Fig. 2 is a rear elevation of the same. Fig. 3 is a section taken on line 3 3 of Fig. 1. Fig. 4 is an elevation of the side opposite that illustrated in Fig. 1. Fig. 5 is a section taken on line 5 5 of Fig. 1. Fig. 6 is a section taken on line 6 6 of Fig. 1. Fig. 7 is a bottom plan view of the same.

As shown in said drawings, the essential or material feature of my design consists in a lifting-pin provided at its top with a laterally-extended flange lying in a plane at right angles with the same, and provided above said flange is an eye. The sides of the pin are plane, with the exception of one of the same, which is provided with a longitudinal groove, as indicated in Fig. 1. Said grooved side ex-

tends parallel with the opposite side to a point indicated by *a* on Figs. 1, 2, 3, and 5, and at which point it inclines outwardly to a point indicated by *a'*, and from thence extends downwardly parallel to the opposite side, as indicated in Fig. 2. Said groove or channel is wider from the point *a* to the flange surrounding the head of the pin than from the point *a'* to the lower extremity of the same. The lower end of the pin is cut away on one side, as indicated, for approximately one-half the width of the pin and inclines upwardly from said grooved side. The remaining portion of said end surface is slightly rounded over adjacent to such inclined or beveled surface on the rear side of the same, as indicated on Figs. 4 and 7.

Having described my invention, what I claim as new, and desire to secure by Letters Patent, is—

The design for a lifting-pin for car-couplers, substantially as shown and described.

In testimony whereof I have hereunto subscribed my name in the presence of two subscribing witnesses.

PHILLIP HIEN.
